(74) Attorney, Agent, or Firm — Tuggle Duggins P.A.;
Blake Hurt(57) **CLAIM**

The ornamental design for a staple, as shown and described.

DESCRIPTION

FIG. 1 is a top, front, right side perspective view of a staple showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a bottom plan view thereof;

FIG. 7 is a top plan view thereof; and,

FIG. 8 is a top, front, left side environmental perspective view thereof, showing the staple with a series of staples. The broken lines showing of the staples and staple holder strip in FIG. 8 illustrates the environment of the claimed design and forms no part thereof.
